UNITED STATES PATENT OFFICE,

GEORGE H. STOUT, OF DENVER, COLORADO, ASSIGNOR OF ONE-HALF TO
LUCIUS A. TURNER, OF DENVER, COLORADO.

GRAVITY-LOCK.

SPECIFICATION forming part of Letters Patent No. 739,945, dated September 29, 1903.

Application filed February 7, 1903. Serial No. 142,410. (No model.)

To all whom it may concern:

Be it known that I, GEORGE H. STOUT, a citizen of the United States, residing at Denver, in the county of Denver and State of Colorado, have invented certain new and useful Improvements in Gravity-Locks, of which the following is a specification.

My invention relates to improvements in gravity-locks for use upon doors, and when 10 constructed as shown involves several novel features having special value in mortise-locks for communicating doors.

The object of my invention is to construct a lock the bolt and tumblers of which are 15 held in position by gravity and to dispense with all springs or other devices liable to get out of order.

Referring to the accompanying drawings, Figure 1 is a side elevation of my improved 20 lock, showing in full lines the bolt in its shot or locked position with the twin tumblers and twin safety-latches turned in positions to lock the bolt and showing in dotted lines the same parts in their retracted or unlocked 25 positions. Fig. 2 is a sectional view taken on the line $x'y$ of Fig. 1, showing the position of the parts when the key has been inserted and passed all baffles and is ready to be turned to retract both the twin tumblers. 30 Fig. 3 is a similar sectional view showing the position of the parts when the key has been turned to unlock the tumblers and is ready to be withdrawn. Fig. 4 is a partial sectional view on the line $x'y$ of Fig. 1, showing the 35 key as having been pushed through the slots in the scutcheon side plate and baffle-plate and striking against and stopped by the central partition. Fig. 5 is a partial sectional view on the line zw of Fig. 1, showing the 40 key as having been pushed past the central partition and having entered the wide slot in the opposite baffle-plate. Fig. 6 shows the central partition. Fig. 7 shows one of the two identical baffle-plates. Fig. 8 is a 45 view of that portion of the side plate surrounding the key-entrance.

The lock-case 1 is preferably stamped from sheet metal and has one or both side plates 2 removable. The face-plate 3 has a bolt-hole 50 4 near its top. The bolt 5 is formed of a

heavy plate or casting and is pivoted at its rear lower end 6 to the side plates, so that its upper end, which is diagonal to its pivot, will be projected by gravity through the bolt-hole in the face-plate 3 and into the keeper 55 (shown in dotted lines) on the door-jamb. A stud or stop 7, projecting from one of the side plates, passes through a slot 8 in the bolt-plate and limits the backward and forward thrust of the bolt, so as to prevent it 60 from injuring the more delicate parts of the lock. The bolt is retracted by the usual square-shanked door-knob, which passes through the square hole 9 and may serve as the pivot of the bolt. 65

In the upper rear corner of the lock are twin tumblers 10 and 11, which turn upon a barrel-pivot 12, having bearings 13, Fig. 5, in the side plates. These tumblers are shaped so that when the bolt is shot they may be 70 turned so that their point 14 will enter a notch 15 in the rear edge of the bolt. This notch is preferably placed at a point slightly below the circumference of a circle centered at the pivot of the bolt and passing through 75 the center of the tumbler bearing or pivot, so that a quick turning and twisting of the door-knob could not jar the tumblers up and back, as might happen if the notch were placed above the line of such a circle. Between these tumblers 10 and 11 is a central 80 partition 16, Fig. 6, having a circular opening 17 for the tumbler-barrel 12. Slots 18 and 19 branch off from said circular opening for a purpose presently explained. One or 85 more baffle-plates 20, having the circular opening 21, with branch slots 22 and 23, are arranged in a similar manner, preferably between the partition and tumblers. These baffle-plates are of the same shape as the 90 upper part of the central partition, but are shorter, so as not to interfere with the movements of the twin safety-latches located below and presently described. Below the twin tumblers 10 and 11 and at the rear of the bolt 95 are the twin safety-latches 24 and 25, located on either side of the central partition and each turning on a squared spindle 26 and having any suitable bearing in the side plates and central partition. The spindles extend 100

to the outside of the door and have knobs 27 on their outer ends. These twin safety-latches are separated from each other by the central partition, which at this point has no opening, 5 so that they are perfectly independent in their movement. These twin safety-latches when turned to the position shown by full lines in Fig. 1 fall into a notch 28 in the rear edge of the gravity-bolt 5, which notch is preferably 10 located on or below the circumference of a circle centered at the pivot of the bolt and which circle passes through the pivot of the safety-latch for the same reason hereinbefore explained with reference to the notch 15 and 15 tumblers 10 and 11. Their unlatched position is shown in dotted lines in Fig. 1.

The door being locked and all of the parts being in the position shown by full lines in Fig. 1 and it being desired to unlock the same, 20 a key 29, having a web 30, notched so as to leave two tangs for projecting ends 31 32, is pushed into the eyed slot 33 in the tumbler-bearing barrel 12 and through a slot 34, Fig. 8, in the side plate and into a slot 35 in the tumbler 10 and also into the corner 36 of the wide slot 22 in the baffle-plate 20, Fig. 7. At this position it strikes the central partition and must be turned until its tang 31 reaches the corner 37 of the wide slot 22. It is then 25 pushed into and through the slot 18 in the central partition and into the wide slot 22 in the baffle-plate on the opposite side of the central partition; but at this position the other tang 32 on the key-web will strike the side 30 plate and the key must be turned back, its tang 31 passing from corner 37 to corner 36 of the wide slot 22 of the opposite baffle-plate until the tang 32 can enter the slot 34, Fig. 8. The key is then pushed home, its web-tang 35 31 entering the slot 35' in the opposite tumbler 11 and its web-tang 32 entering the slot 35 in the rear tumbler 10. The key is now turned around, so as to lift both tumblers 10 and 11 out of the notch 15 in the rear edge of 40 the bolt, and rests against the back of the lock-casing, as shown by the dotted lines in Fig. 1, and the key may then be withdrawn, slots 23, Fig. 7, in the two baffle-plates, slot 19, Fig. 6, in the central partition, and slot 50 38, Fig. 8, in the lock-casing being provided for this purpose. When the parts are in the unlocked position, slots 23, 19, and 38, just described, all coincide, and the key is pushed clear home and then turned so as to place the 55 tumblers in the position shown in full lines in Fig. 1. To now withdraw the key after locking, the movements of the key to avoid the baffle-plates and central partition are just the reverse of the movements described in 60 unlocking.

When my new lock is used as a communicating lock—that is, on doors communicating two rooms—its many advantages are practically and most clearly seen. Should the lock 65 be used on the communicating door between

two adjacent rooms of a publichouse, a former tenant, who had rented the said rooms "en suite," might have a key to fit the lock and when afterward occupying only one of said rooms could use said key to unlock the communicating door; but, as has been described, my new lock comprises not only tumblers accessible to a key from opposite sides, but also a pair of twin safety-latch tumblers 24 25, which are entirely separated from each other 70 by a central partition in the lock that completely isolates one side of the lock from the other and a tenant of one room can secure the bolt against even a key made to operate the twin tumblers. 75

I am aware that mortise and other locks have been made with partitions or diaphragms separating one side of the lock from the other and in which the tumblers accessible from one side of the partition are connected to the 80 tumblers on the other side, so that the separated tumblers act in unison, and also of locks in which the opposite tumblers are independent but capable of being unlocked only from the locked side; but I am not 85 aware that locks have been made as I herein describe and hereinafter claim and in which a pair of supplemental tumblers which are entirely separated by said partition and are each accessible to only one side of the lock 90 and coact separately with the tumblers accessible from both sides of the lock to more securely lock the bolt. Obviously the lock may be provided with several baffle-plates in addition to and differently disposed than 95 those described and wards and ward-notches provided to vary the construction of the lock and the key required to open it. 100

I claim—

1. The combination, in a gravity-lock, of 105 two independently-movable tumblers both accessible to a key from opposite sides of the lock, and two independently-movable latches each accessible from only one side of the lock, and a central partition separating said 110 tumblers and said latches and perforated to give access to a key from either side of the lock at the place of its division of said tumblers and imperforate at the place of its division of said latches substantially as described. 115

2. The combination in a lock with a bottomly-pivoted swinging gravitating bolt, and twin tumblers independently movable and twin latches independently movable, of a central partition located back of the rising swing of said bolt and separating both the tumblers and the latches, substantially as described. 120

3. In a lock, the combination with a bottomly-pivoted gravitating bolt, two independently-movable tumblers both accessible to a key from opposite sides of the lock and two independently-movable latch-tumblers each accessible from only one side of the lock, 125 a central partition notched or perforated to 130

give access to a key from either side of the lock at the place of its division of said tumblers and imperforate at the place of its division of said latch-tumblers and baffle-plates located above the swing of the said latches upon either side of said partition and perforated by notches non-coinciding with the notches in said central partition to give ac-

cess to a key from either side of the lock, substantially as described.

In testimony whereof I affix my signature in presence of two witnesses.

GEORGE H. STOUT.
